(57) **CLAIM**

The ornamental design for a grow light for plants, as shown and described.

DESCRIPTION

FIG. 1 is a front, left, top perspective view of a grow light for plants showing my new design;

FIG. 2 is a front, right, top perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a perspective view of the grow light for plants shown in an environment of use;

FIG. 10 is an enlarged view of the encircled area 10 of FIG. 2;

FIG. 11 is an enlarged view of the encircled area 11 of FIG. 3; and,

FIG. 12 is an enlarged view of the encircled area 12 of FIG. 6.

The broken lines shown on the drawings depict portions of the grow light for plants that form no part of the claimed design. The dot-dash lines depict the enlarged view boundaries that do not form part of the claimed design. The additional broken lines shown in FIG. 9 depict environment only that forms no part of the claimed design.
